UNITED STATES PATENT OFFICE.

HOMER WRIGHT, OF PITTSBURG, PENNSYLVANIA.

COVER FOR JUGS.

SPECIFICATION forming part of Letters Patent No. 244,413, dated July 19, 1881.

Application filed April 16, 1881. (No model.)

To all whom it may concern:

Be it known that I, HOMER WRIGHT, of Pittsburgh, in the county of Allegheny and State of Pennsylvania, have invented a new and useful Improvement in Covers for Jugs, &c.; and I do hereby declare the following to be a full, clear, and exact description thereof.

My invention relates to tops or covers for pitchers, jugs, mugs, &c.; and it consists in the mode of forming and arranging the parts of the same so as to form a durable and effective cover.

I will now describe my invention so that others skilled in the art may manufacture the same, reference being had to the accompanying drawings, forming a part of this specification, in which—

Figure 1 is a vertical sectional view of the top or cover. Fig. 2 is a detached plan view 20 of the lid of the same. Fig. 3 is a detached perspective view of the casting which forms the handle of the lid and pintles of the hinge. Fig. 4 is a detached cross-sectional view of the neck, showing the hinge and spring. Fig. 5 25 is a plan view of the body of the cover. Figs. 6 and 7 are perspective views of the dies for forming the eye of the hinge on the body of the cover.

Like letters refer to like parts wherever they 30 occur.

In the drawings, *a* represents the lid of the cover, which may be of any suitable sheet metal. This lid is cut and stamped from a single piece of metal into the form shown in Fig. 2 by any suitable machinery, so as to have near or in rear of its center a slot or opening, *b*, and at its rear end a projecting thumb-piece, *c*, directly in front of which is an outward bulge, *d*, which makes a concavity on the inner surface of the lid.

e is the body of the top or cover, which is cut and stamped from a single piece of sheet metal in the form shown, so as to have a lip, *e'*, and also an inside flange or base, *e''*. In the back 45 end or side of the body thus formed are stamped two openings, *e³*, which open in a line cutting the circumference of the body. These openings are formed by inverting the body and placing its back edge upon the die *m* under the 50 plunger *n*, which, descending, cuts and forces

in the corner of the body at two opposite points, forming the holes *e³* for the reception of the pintles of the hinge.

The pintles of the hinge for connecting the body *e* and lid *a* and the knob for opening the lid are made in one piece, preferably of a soft metal, cast in the form shown in Fig. 3, having a body, *f*, from which project two arms, *f'*, the pintles *f²* projecting out from and at right angles to the ends of the arms *f'*, a raised disk, *f³*, on the body *f*, a lug, *f⁴*, projecting slightly upward and in front of the body *f*, and a knob, *f⁵*, on top of the disk *f³*.

Below and around the body *e* of the cover is attached, by solder or other suitable means, a 65 collar, *h*, which collar is attached to the neck of the jug.

The several parts which together form the top are attached to each other as follows: The body *e* of the cover is first attached to the collar *h* by solder or in any other suitable manner. The pintles *f²* are placed between the holes *e³* in the body *e*, and the two arms *f'* are spread apart by the use of a suitable tool sufficiently to cause the pintles to enter the openings *e³*. The knob *f⁵* is then passed through the opening *b* in the lid *a*, so that the body *f* shall be below or on the inner surface of the lid *a*, while the knob *f⁵* and lug *f⁴* are on the outer surface and the disk *f³* fills the opening 80 *b* and projects slightly above the outer surface of the lid *a*. The disk *f³* is then stamped by suitable machinery, so as to spread the soft metal over the outer edges of the opening *b*, and thereby rivet the lid firmly to the body *f*. 85

In the base *e²* of the body *e* of the cover is a small hole or opening, through which passes one end of a spiral spring, *k*, for closing and holding the lid shut, the other end of which passes through a similar hole in the body *f* of the casting. This spring may be easily inserted after the different parts of the top are put together.

The purpose of the thumb-piece *c* is to open the lid, and the bulge *d* is to allow the lid to 95 pass over the ring *e*, when opened, without striking it.

The advantages of my invention are the simplicity and cheapness of the mode of construction and the compactness, durability, and 100

lightness of the cover produced, and the fact that the lid is always held close, excluding dirt and flies.

Having thus described my invention, what I claim, and desire to secure by Letters Patent, is—

1. A bifurcated hinge-piece for jug-tops, made of soft metal, with a pintle on each arm extending at an angle and capable of being forced into the eye of the hinge by bending the arms, substantially as and for the purposes described.

2. The combination of a bifurcated hinge-piece attached to the lid, each arm of said

hinge-piece having a lateral pintle extending 15 from its end, with a base ring or body having the eyes of the hinge punched through it, substantially as and for the purposes specified.

3. The combination, in a jug-top, of the ring, the lid, and a spiral spring placed inside of the 20 jug and connected to said ring and lid at its opposite ends.

In testimony whereof I have hereunto set my hand.

HOMER WRIGHT.
